UNITED STATES PATENT OFFICE.

HENRY H. DUPONT, OF INDIANAPOLIS, INDIANA.

SHOWER-STALL.

1,112,200.

Specification of Letters Patent. Patented Sept. 29, 1914.

Application filed July 5, 1913. Serial No. 777,409.

To all whom it may concern:

Be it known that I, HENRY H. DUPONT, a citizen of the United States, residing at Indianapolis, in the county of Marion and State of Indiana, have invented a new and useful Shower-Stall, of which the following is a specification.

The object of my invention is to produce a sanitary shower bath stall which may be readily erected for use, either in new or old buildings, said stall consisting of enameled cast iron sections which may be erected without the use of fastening devices contacting with the enameled surfaces.

15 The accompanying drawings illustrate my invention.

Figure 1 is a perspective view of that form of my device constructed for erection within a recess or pocket formed in a wall or partition; Fig. 2 a central vertical section of the structure shown in Fig. 1; Fig. 3 is a section on line 3—3 of Fig. 2; Fig. 4 a front elevation of an embodiment of my device in the form adapted for erection 20 in a corner between two walls or partitions; Fig. 5 a horizontal section of the structure shown in Fig. 4; Fig. 6 a detail of the joint between two of the adjacent top members; Fig. 7 a detail of a desirable form of joint 25 between one of the wall members and the forward finishing plate; Fig. 8 a fragmentary section of the joint between a top plate and a vertical plate; Fig. 9 a fragmentary sectional detail of the joint between one of the vertical plates and the receptor; Fig. 10 a fragmentary horizontal section of a desirable joint between two vertical members; and Fig. 11 a horizontal fragmentary section of the joint between one of the vertical 30 members and a front finishing plate of the form shown in Fig. 5.

In the drawings 10 indicates the slightly dished bottom plate of a receptor conveniently provided with a vertical flange or rim 45 11 the lower end of which, below bottom 10, forms the support for the structure and the upper end of which is projected sufficiently above the bottom 10 to form a container of adequate volume to insure against any overflow. At the front of the basin the upper edge of flange 11 is turned outwardly and downwardly, as indicated at 12, so that an arc-shaped finishing plate 13, with side wings 14, 14, may be projected thereunder. 50 Beginning at each end of the down-turned

portion 12 the upper edge of flange 11 is outwardly displaced and then upwardly extended, as indicated at 15, Figs. 2 and 9. Bottom 10 is provided with a suitable outlet 10' adapted to be connected with the upper 60 end of the waste pipe 10''. Lip 12 is purposely lower than the part 15 so that in case of accidental overflow, it will take place in front of the device where it will be immediately visible.

The receptor just described is made of cast iron and the upper surface of bottom 10 and the inner surface of flange 11, together with the upper and outer surface of lip 12, is enameled or glazed in the usual manner of glazing bath-room articles, but it is a well known fact that in producing articles of this kind it is practically impossible to glaze under surfaces or to glaze both outer and inner surfaces of a vertical 75 flange or member. It is for this reason that I provide the lip 12 which is sufficiently separated from the main body of the flange 11 to permit the insertion of the plate 13, as by this arrangement the enameling of the receptor 10 may extend only to the lower edge of lip 12 and the desired finish below this lip is obtained by the glazed outer face of the plate 13 and wings 14.

The vertical wall of the stall is conveniently formed in several sections 16, 17 and 18 each of which at its lower end is provided upon its rear face with a downwardly and outwardly extending finger or flange 19 which is sufficiently separated from the 80 lower end of the main body of the plate to not only receive the upwardly projecting portion 15 of flange 11 but also to receive a packing 20 of putty or other suitable substance.

The joint just described holds the lower ends of the vertical wall sections in proper position and their adjacent edges are connected by a somewhat similar joint but, in order that the vertical edges of the sections 100 shall not be too noticeable from the entrance opening of the stall the sections 16 and 18 are mates, right and left, each of said sections at its rear vertical edge being provided on its back with a finger 22 spaced from the main body of the plate so as to form a pocket 23 for the reception of the adjacent edge of the plate 17 and also so as to receive a packing 24. By this arrangement, an 105 accidental leakage into this joint will flow 110

downwardly and, striking the upper edge of part 15 of flange 11 at its inner face, will flow down into the receptor.

- The upper ends of the vertical wall plates 6 are held together by the top plates 25, 25, 26, 26, each of which is provided with a down-turned flange 27 lying inside of the vertical wall plates and having their vertical faces enameled as indicated in Fig. 8. 10 Each of the top plates is also provided on its under face with one or more downwardly extending lugs 28 which are spaced apart from the flanges 27 a distance sufficient to permit the insertion of the upper ends of 15 the vertical plates 16, 17 or 18. At their adjacent portions the plates 25 and 26 are formed to overlap as indicated in Fig. 6, the arrangement being such that all exposed faces of these plates may be readily enameled by the present known processes. The top plates 25, 25 do not meet each other but are spaced apart a distance substantially the same as the distance between the forward vertical edges of the plates 16 and 17. 20 and at their adjacent corners these plates are provided with short vertical pins 30 over which may be sleeved the ends of a curtain rod 32, this curtain rod thus forming a chord to that portion of the arc of the 25 receptor which is provided with the finishing lip 12. The forward vertical flanges of the plates 25, 25, overlie the upper ends of the finishing plates 33, 33 each of which at its lower end is provided at the rear with 30 a flange or finger 19 so as to overlie the upper edge of the adjacent wing 14. The outer edge of each plate 33 is adapted to be slightly buried in the adjacent wall of the pocket or recess 34 (indicated in dotted 35 lines in Fig. 3) while the inner edge is curled rearwardly and outwardly as indicated at 35 Fig. 3 to receive the forward edge of the vertical plate 16 or 18, as indicated in Fig. 7. 40 The finishing plates 33' (Fig. 5), are practically the same as finishing plates 33 except that they need to be wider and, because they lie substantially tangentially to the adjacent plate 16 or 18, the edge 35' 45 is preferably of the form shown in Fig. 11, the outer face of the vertical wall 16 being ground away, as indicated at 36 (Fig. 11), before the wall 16 is enameled on its inner face. This preliminary grinding makes 50 room for the packing 37. In order to make the structure more rigid, although not absolutely necessary, I provide the rear faces of the vertical wall sections, 55 near their adjacent edges, with rearwardly extending flanges 38 which are perforated to receive clamping bolts 39. These flanges prevent warping of the plates during enameling.

In order to insure against discharge of 60 water from the stall the spray nozzle 40 is

carried by a pipe 41 which is projected through the vertical plate 16 and is directed rearwardly. The supply pipes, indicated at 42 in dotted lines in Fig. 3 may then be conveniently brought up in the space behind one of the finishing plates 33, said finishing plate being provided with an opening 43 through which the controlling valve 44 may operate. The usual stop valves may be placed within the supply pipes and rendered accessible through comparatively small openings 45 in the finishing plate 33. 70

The receptor, the vertical walls and the top plates are to be formed of cast iron and the several exposed faces are subjected to a common enameling process such as used in the production of bath tubs of a well known type, and it will be noted that the formation of the various parts is such that only those surfaces are exposed to view and to the action of the water as can be readily and adequately enameled in the manner described. In erecting the structure a special recess, as indicated by dotted lines in Fig. 3, or the structure may be mounted in a corner 80 as indicated in Fig. 5, and the receptor will be connected to the waste pipe, said waste pipe serving to retain the receptor in proper position. The other portions may be assembled, in the manner set forth, without the use of any clamping or fastening means which will be at all liable to crack or otherwise injure the enameled surfaces. The structure may be readily erected in existing rooms and is entirely sanitary. By arranging the curtain rod 32 as a chord to the exposed arc of the receptor to the entrance, the lower end of the curtain will lie entirely within the receptor and thus prevent any dropping or splashing on the floor outside 90 of the structure. It will also be apparent that the user may completely regulate the flow of water without being wet during the 95 operation. 100

I claim as my invention:

1. A sanitary shower-stall, comprising an enameled receptor having an upstanding circular flange, an enameled iron wall having a socket at its lower end fitting said upstanding flange, said wall being composed of a plurality of parts, adjacent parts of the wall meeting on a vertical joint formed by a vertical socket along the edge of one part and a coöperating tongue along the edge of the other, said wall parts being provided with exterior lugs near the edges forming such joints, and bolts coöperating with said lugs to hold the wall parts together, said receptor and said wall having the enamel on the inner surface. 110 115 120

2. A sanitary shower-stall, comprising an enameled receptor having an upstanding circular flange, and an enameled iron wall having at its lower end a socket comprising two depending spaced flanges between which fits 125 130

said upstanding flange, said receptor and said wall having the enamel on the inner surface and having their inner surfaces substantially flush with each other.

5 3. A sanitary shower-stall, comprising an enameled receptor having an upstanding circular flange, an enameled iron wall having a socket at its lower end fitting over said upstanding flange, said receptor and said wall having the enamel on the inner surface and said wall extending less than all the way around the edge of the receptor so as to leave a doorway, a pair of finishing plates of iron enameled on the forward face, which finishing plates are provided with inturned flanges at their inner edges to overlap the edges of the doorway, and a third finishing plate enameled on the forward face and fitting against the front of the receptor below the doorway and beneath the first named finishing plates, said third finishing plate being provided at its upper edge and beneath said first finishing plates with a tongue and said first finishing plates being provided at their lower edges with sockets which fit over said tongue on the third finishing plate.

4. A sanitary shower-stall, comprising an enameled receptor having an upstanding circular flange, an enameled iron wall having a socket at its lower end fitting over said upstanding flange, said receptor and said wall having the enamel on the inner surface and said wall extending less than all the way around the edge of the receptor so as to leave a doorway, a pair of finishing plates of iron enameled on the forward face, which finishing plates are provided with inturned flanges at their inner edges to overlap the edges of the doorway, and a third finishing plate enameled on the forward face and fitting against the front of the receptor below the doorway and beneath the first named finishing plates.

45 5. A sanitary shower-stall, comprising an enameled receptor having an upstanding circular flange, an enameled iron wall having a socket at its lower end fitting over said upstanding flange, said receptor and said wall having the enamel on the inner surface and said wall extending less than all the way around the edge of the receptor so as to leave a doorway, a pair of finishing plates of iron enameled on the forward face, which finishing plates are provided with inturned flanges at their inner edges to overlap the edges of the doorway, and a third finishing plate enameled on the forward face and fitting against the front of the receptor below the doorway and beneath the first named finishing plates, the upstanding flange of the receptor having its upper edge turned forward below the doorway to form a reverse flange which fits over the upper edge of said third finishing plate below said doorway.

6. A sanitary shower-stall, comprising an enameled receptor having an upstanding circular flange, an enameled iron wall having a socket at its lower end fitting over said upstanding flange, said receptor and said wall having the enamel on the inner surface and said wall extending less than all the way around the edge of the receptor so as to leave a doorway, a pair of finishing plates of iron enameled on the forward face, which finishing plates are provided with inturned flanges at their inner edges to overlap the edges of the doorway, and a cover plate which extends outward from said wall at the top and backward from said finishing plates at the top, said cover plate being enameled on its upper side and being provided at the top of said wall and at the top of said finishing plates with a down-turned flange projecting along the inside face of said wall and the forward face of said finishing plates.

7. A sanitary shower-stall, comprising an enameled receptor having an upstanding circular flange, an enameled iron wall having a socket at its lower end fitting over said upstanding flange, said receptor and said wall having the enamel on the inner surface, and a top plate which extends outward from the upper edge of the wall and is provided with a down-turned flange which extends downward along the inside surface of the wall from the top thereof.

8. A sanitary shower-stall, comprising a receptor having an upstanding flange a portion of which is higher than the remainder and outwardly offset, and a stall wall cooperating with said higher portion of said flange by means of a socket comprising two spaced depending flanges between which said upstanding flange is received.

9. A sanitary shower-stall, comprising an enameled receptor having an upstanding flange, and an enameled iron wall having at its lower end a socket comprising two depending spaced flanges between which fits said upstanding flange, said wall being composed of a plurality of parts, adjacent parts of the wall meeting on a vertical joint formed by a vertical socket along the edge of one part and a co-operating tongue along the edge of the other, said receptor and said wall having the enamel on the inner surface and having their inner surfaces substantially flush with each other.

10. A sanitary shower-stall, comprising an enameled receptor having an upstanding flange, an enameled iron wall having a socket at its lower end fitting over said upstanding flange, said receptor and said wall having the enamel on the inner surface and said wall extending less than all the way around the edge of the receptor so as to leave a doorway, and a pair of finishing plates of iron enameled on the forward face, which finishing plates are provided with in-

turned flanges at their inner edges to overlap the edges of the doorway.

11. A sanitary shower-stall, comprising an enameled receptor having an upstanding flange, an enameled iron wall having a socket at its lower end fitting over said upstanding flange, said receptor and said wall having the enamel on the inner surface and said wall extending less than all the way 5 around the edge of the receptor so as to leave a doorway, a pair of finishing plates of iron enameled on the forward face, which finishing plates are provided with inturned flanges at their inner edges to overlap the 10 edges of the doorway, and a third finishing plate enameled on the forward face and fitting against the front of the receptor below the doorway and beneath the first named finishing plates.
12. A sanitary shower-stall, comprising an enameled receptor having an upstanding flange, an enameled iron wall having a socket at its lower end fitting over said upstanding flange, said receptor and said wall 15 having the enamel on the inner surface, and

a top plate which extends outward from the upper edge of the wall and is provided with a down-turned flange which extends downward along the inside surface of the wall from the top thereof, said cover plate being 30 enameled on its upper surface.

13. A sanitary shower-stall, comprising an enameled receptor having an upstanding flange, an enameled iron wall having a socket at its lower end fitting over said upstanding flange, and a top plate which extends outward from the upper edge of the wall and is provided with a down-turned flange which extends downward along the 35 inside surface of the wall from the top 40 thereof.

In witness whereof, I have hereunto set my hand at Indianapolis, Indiana, this third day of July, A. D. one thousand nine hundred and thirteen.

HENRY H. DUPONT.
